DESIGN FOR A GLIDER SWING

Cecil H. Buck, Birmingham, Ala.

Application June 8, 1946, Serial No. 130,555

Term of patent 3½ years

(Cl. D15—11)

To all whom it may concern:

Be it known that I, Cecil H. Buck, a citizen of the United States, residing at Birmingham, in the county of Jefferson and State of Alabama, have invented a new, original, and ornamental Design for a Glider Swing, of which the following is a specification, reference being had to the accompanying drawing, forming a part thereof.

In the drawing,

Fig. 1 is a plan view,

Fig. 2 is a side elevational view, and

Fig. 3 is an end view of a glider swing, showing my new design.

I claim:

The ornamental design for a glider swing, substantially as shown.

CECIL H. BUCK.
